UNITED STATES PATENT OFFICE.

LOUIS JOS. BRUNE, OF ALGIERS, LOUISIANA.

WINDOW-SASH HOLDER AND LATCH.

1,257,457.

Specification of Letters Patent. Patented Feb. 26, 1918.

Application filed October 18, 1917. Serial No. 197,320.

To all whom it may concern:

Be it known that I, LOUIS J. BRUNE, a citizen of the United States of America, residing at Algiers, in the parish of Orleans 5 and State of Louisiana, have invented new and useful Improvements in Window-Sash Holders and Latches, of which the following is a specification.

This invention has reference generally to 10 improvements in that class of inventions known as builders' hardware, and more particularly relates to a window sash holder and latch.

As the primary aim and object the present 15 invention contemplates the provision of a device of the above mentioned character designed for application on the stile of a window casing and on the lower sash for either removably locking the window sash in a 20 closed position or else removably locking the sash in various positions of adjustment.

More particularly the present invention embraces the provision of a device of the above mentioned character wherein a pair of 25 relatively movable manually operable sections are attached to the window sash and are capable of being readily extended to assume a locked position and subsequently held in such position to prevent relative 30 movement of the sash with respect to the casing.

It is a more specific object of this invention to provide a window sash holder or latch wherein the construction thereof is 35 novel and permits of the convenient manual operation thereof while the parts are so arranged that when placed in an extended or locked position the sash cannot be moved in any direction until the releasing means is 40 actuated.

It is an additional object of this invention to provide a device of the above mentioned character which is simple in construction, thoroughly reliable and efficient in its purpose and inexpensive in manufacture.

Other objects will in part be obvious and in part hereinafter set forth.

The invention accordingly consists in the features of construction, the combination of

elements and the arrangement of parts 50 which will be exemplified in the construction hereinafter described and the scope of the application of which will be indicated in the appended claims.

The invention is clearly set forth in the 55 accompanying drawings, in which:—

Figure 1 is a front elevation of the device applied and arranged in an open position;

Fig. 2 is a front elevation of the same sash 60 in locked position;

Fig. 3 is a longitudinal detail of the device;

Fig. 4 is a perspective detail.

Similar characters of reference are employed in all the above described views, to 65 indicate corresponding parts.

Referring now, more particularly, to the accompanying drawings, there is provided a window casing 1 in which is slidably mounted a lower sash 2 while secured to the 70 stile 3 of the casing and the sash 2 is the improved holding and latching device, indicated in its entirety by the numeral 4.

With a view toward providing the improved holding and latching device a rack 75 bar 5 is employed and is formed on its outer face with a series of teeth 6 while the respective ends are reduced and secured to the inner surface of one of the stiles near the sill through the instrumentality of suitable fasteners 7.

Coöperating with the teeth of the rack bar is the improved holding or latching member 8. This member consists of an inner section 9 and an outer section 10. The inner section 85 is pivoted for vertical swinging movement to the outer surface of the lower portion of the sash 2 through the instrumentality of suitable fasteners 11 while the adjacent ends of the sections 9 and 10 are shaped to form 90 a rule joint 12 and are pivotally supported with respect to each other through the instrumentality of the shank 13 of a knob 14. The inner end of the shank of course is slightly flattened as at 15 so as to prevent 95 accidental disengagement of the sections. A head 16 is formed on the outer end of the outer section 10 while the outer face of the

head is formed or provided with a notch 17 designed for engagement with any one of the teeth 6 of the rack bar 5. In operably connecting the outer section 10 to the sash an arcuate attaching member 18 is counter-sunk in the outer face of one side of the sash 2 near the lower portion thereof being secured through the instrumentality of a suitable fastener 19. This member is designed to 5 form a groove or passage 20 which is disposed below the correspondingly shaped slot 21, of a width less than the width of the passage or groove. One end of the slot is enlarged to form an opening 22 while inscribable through the opening is a head 23 of a bolt 24. The shank of the bolt operates through the slot 21 and also engages a lug 25 formed on the section 10. A wing nut 26 is mounted on the outer projecting end of 10 the bolt and serves to clamp the outer section 10 in various adjusted positions such as indicated in Figs. 1 and 2 of the drawings and serving to either hold the notched head 16 out of engagement with any of the teeth of 15 the rack so that the sash may be raised or lowered as desired or else hold the sash against any movement whatever.

The mode of operation of the present invention may be reviewed as follows:—

30 Assuming that the parts have been assembled in the manner described and as indicated in the drawings, when it is desired to lock the sash 2 in a closed position the section 9 is swung downwardly about its pivot 35 11 preferably by engaging the knob 14 until the shoulders of the rule joint abut each other. During this downward swinging movement of the section 9 the section 10 will also swing downwardly and outwardly 40 and assume the position shown in Fig. 2, the notch 17 in the head thereof engaging one of the teeth 6 in the rack bar. The wing nut 26 of course is loose during this adjustment of the parts and after the parts have 45 been arranged as described the wing nut is tightened so as to clamp the section 10 in a stationary position and by reason of the fact that the notched head engages one of the teeth and the rule joint is positioned slightly beneath the plane of the head and the pivoting point 11 of the section 9 it is impossible 50 to raise or lower the sash. In a similar manner the sash may be held in various positions of adjustment and cannot be opened from 55 the outside. To release the parts it is only necessary to loosen the wing nut and break the joint upwardly which action causes the bolt 24 to move through the slot and consequently draws the head from engagement 60 with the teeth permitting the sash to freely move.

It is believed that in view of the foregoing description, a further detailed description of

the operation of the invention is entirely unnecessary. Likewise it is believed that the 65 advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not 75 in a limited sense. It is also to be understood that the language used in the following claims is intended to cover all the generic and specific features of the invention herein described and all statements of the scope of 80 the invention which as a matter of language might be said to fall therebetween.

Having thus described the invention what is claimed as new and desired to be secured by Letters Patent is:—

85 1. A window sash holder and latch including a rack bar adapted to be secured to the inner surface of one side of the window casing, a holding and latching member composed of relatively movable sections, means 90 for pivoting one of the sections to a window sash, means for slidably connecting the other section to the window sash and for clamping the same section at times rigid with the sash, and a notched head formed 95 on the outer end of the last mentioned section for engagement with any one of the teeth of the rack bar and designed to be held in such position when the adjacent connected ends of the sections are moved 100 downwardly and clamped.

105 2. A window sash holder and latch including a rack bar adapted to be secured to the inner surface of one side of a window casing, a holding and latching member composed of an inner section and an outer section the adjacent ends of the sections being shaped to form a rule joint, a knob, a shank extending from the knob and pivotally connecting the joint at the ends of the sections, 110 means for pivotally connecting the inner end of the inner section to a window sash, an enlarged head formed on the outer end of the outer section and designed for engagement with any one of the teeth of the 115 rack bar, an arcuate attaching member adapted to be countersunk in the sash and formed with a passage and with a slot above the passage of a width less than the passage and further provided with an opening at one 120 end of the slot for establishing communication with the passage, a bolt operating through the slot and formed with a head inscribable through the opening and operating in the passage, the projecting end of the bolt 125 passing through the outer section at a point

substantially midway the ends thereof, the knob being designed to move the adjacent ends of the sections downwardly and slide the outer section so that the head will engage one of the teeth of the rack, and a wing nut mounted on the projecting end of the

bolt for removably clamping the outer section in frictional engagement with the attaching plate to prevent accidental displacement of the head.

In testimony whereof I affix my signature.

LOUIS JOS. BRUNE.
